DESIGN.

J. B. GEORGE.

CARPET.

No. 15,434.

Patented Oct. 7, 1884.

UNITED STATES PATENT OFFICE.

JOHN BELLAMY GEORGE, OF 37 Highbury Hill, County of Middlesex, England, assignor to WILLIAM MANSELL DAINTRY, OF NEW YORK, N. Y.

DESIGN FOR A CARPET.

SPECIFICATION forming part of Design No. 15,434, dated October 7, 1884.

Application filed June 30, 1884. Term of patent 3½ years.

To all whom it may concern:

Be it known that I, JOHN BELLAMY GEORGE, a resident of No. 37 Highbury Hill, in the county of Middlesex, England, have invented and produced a new and original Design for a Carpet, of which the following is a full description, in connection with the accompanying photograph, which represents a face view of my new design for a carpet.

10 This invention relates to a new ornamentation of the face of a carpet, oil-cloth, or analogous fabric.

15 In the accompanying photograph are represented the various parts which enter into my new design. The stripe A contains the ornamental band a and the band b, showing representations of fanciful flowers d d, somewhat resembling those of the poppy plant, and curved twigs e e, set with deeply-serrated leaves, and 20 entwining with each other. The stripe A also contains the ornamental band c. The part B is ornamented with representations of flowers ff, some of which are shown fully open, some as buds, others partly open, said flowers resembling those of the poppy plant, and deeply-serrated leaves g g, grouped with respect to one another and to said flowers, as shown.

I claim—

1. The design for a carpet, the same consisting of the stripe A, having the bands a, b, and c, substantially as shown. 25

2. The design for a carpet, the same consisting of the part B, having the figures ff and g g, grouped substantially as shown.

3. The design for a carpet, the same consisting of the stripe A, containing the bands a, b, and c, and the part B, having the flowers ff and leaves g g, substantially as shown. 35

The foregoing specification of my invention for new and original design for carpet signed 40 by me this 10th day of March, 1884.

JOHN BELLAMY GEORGE.
